CAPSTAN

Otto E. Dever, Burbank, Calif.

Application August 2, 1954, Serial No. 447,111

10 Claims. (Cl. 74—801)

This invention relates to a capstan construction and, while adapted for many different uses, is more particularly adapted to move cargo in airplanes and also to move heavy objects in the open field. Accordingly, this invention contemplates one form of the invention that is, with easy facility, connected to the floor of a cargo airplane, as by conventional fittings provided in said floor. The invention also contemplates a second form that can be connected to any fixed point or object such as a tree or stump, or a large boulder, and thus used in the open field.

An object of the present invention is to provide a power-driven capstan that embodies novel power advantage features which enable the ready handling by the capstan of heavy objects.

Another object of the invention is to provide a motor-driven capstan that embodies novel power gearing between the motor and drum of the capstan which results in a power advantage for said drum.

A further object of the invention is to provide novel and improved means to separably connect the capstan in operative position.

The invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes, preferred embodiments of the present invention, which are given by way of illustration or example only.

In the drawings, like reference characters designate similar parts in the several views.

Fig. 1 is a plan sectional view of a capstan constructed according to the invention, said view being taken on line 1—1 of Fig. 2.

Fig. 2 is a vertical elevational view, partly in section, as taken on line 2—2 of Fig. 1.

Fig. 3 is a vertical and fragmentary elevational and sectional view as taken on line 3—3 of Fig. 1.

Fig. 4 is a plan view of a modification.

Fig. 5 is a side elevational view in quarter section of the capstan shown in Fig. 4.

The present capstan comprises a base 10, a revoluble drum 11 disposed above said base, an electric motor 12 within said drum, power-advantage gearing 13 carried partly by the base, partly by the drum, and partly by the shaft 14 of said motor, and a one-way clutch 15 to obviate backup or backlash of the mechanism. The form of Figs. 1, 2 and 3 embodies means 16 in the base to effect separable connection to tie-down fittings provided as in the floor of a cargo airplane. The form of Figs. 4 and 5 provides said base with a lateral extension 17 adapting the base and capstan to be rendered captive.

In the form illustrated in Figs. 1, 2 and 3, the base 10 has a generally H-shaped form in which the base legs

2

- 20 are connected by an integral cross part 21. In the latter part, the base is provided with a circular hub 22 that has a closed bottom 23, the hub 22 having formed therein a circular inner seat 24 adjacent said bottom and a somewhat larger seat 25 in the upper portion thereof. Although formed as a separate member, a support 26 is seated in seat 25 and is securely fastened to hub 22, as by bolts 27. Said support extends substantially above the upper face of base 10 and is finished as a circular boss 28 that has a central axis coincidental to the center of seat 24.

The drum 11 comprises a vertically disposed portion 29 that is provided with a conically tapered outer surface 30 that is larger at the top than at the bottom. From the bottom, said portion 29 is outwardly and downwardly flared at 31 and then extended as an enlarged horizontal plate part 32 that terminates in a downwardly directed peripheral skirt or flange 33. The upper end of the drum is closed by a cap or cover 34a which may comprise a separate member fixedly bolted to the upper edge of the drum portion 29. Adjacent its lower end, the portion 29 is provided with an inreaching transverse flange 34 that has a central opening.

Inwardly of support 26 and affixed to said flange 34, as by bolts 35, there is provided a hub 36 that is coaxial with support 26. Suitable vertically spaced anti-friction bearings 37 mount hub 36 within the boss 28 of said support and, therefore, rotationally mount the drum 11 above base 10. It will be noted that bearings 37 are large diametrically and, therefore, greatly resist torsion load forces that are applied to the drum and transmit the same through the relatively large and stable boss 28 of the support 26 to the base 10.

The electric motor 12 has its stator or field 38 affixed to the drum and the usual armature or rotor, within the field, affixed to shaft 14. Consequently, said drum and shaft are relatively rotational.

The gearing 13 comprises an internal or ring gear 39 disposed in seat 24 and secured to hub 22 as by bolts 40; a second internal or ring gear 41 having a slightly greater pitch diameter than gear 39, affixed to hub 36 and disposed above and immediately adjacent to gear 39; a sun gear 42 affixed to or formed integrally on shaft 14; a set of twin planetary gears (only one of which is shown in the drawings) and formed with a gear 43 intermeshing with fixed ring gear 39 and sun gear 42 and with a slightly larger gear 44 meshing with ring gear 41; and a freely rotational cage 45 mounting said twin planetary gears 43—44.

The upper end of shaft 14 is engaged in a radial bearing (not shown) provided in the drum cap 34 and the lower end is in thrust engagement with a plate 46 fitted to the center of cage 45 and, in turn, supported on a thrust screw 47 adjustably carried by the bottom wall 23 of hub 22. A radial anti-friction bearing 48 is interposed between an intermediate part of said shaft and both the drum flange 34 and hub 36. The upper end of shaft 14 constitutes an armature shaft for motor 12, and may be formed separately from the lower portion, and be connected by suitable splines. Thus, the armature-mounting end of said shaft may assume any flux-induced endwise position without affecting the gear-provided end.

The clutch 15 is shown as having one part 49 carried by shaft 14 and the other part 50 formed on the hub 36. The clutch is of the usual one-direction type in which part 49 rotates freely in part 50, in one direction, and has a driving or coupled connection with the latter part when turned in the opposite direction.

The means 16 is provided in each of the base legs 20 and is shown as comprising slidible blocks 51 in guides 52 provided in said legs and moved endwise by turnbuckle means 53. Said blocks 51 carry flanged members

54 that are adapted to effect connection with floor fittings, as hereinbefore indicated.

Since both the stator and rotor of the motor 12 rotate with relation to base 10, electric power is brought from the base to the drum by brush means 55. A switch 56 in said base is provided to control operation of the motor.

In operation, the shaft 14 is rotated, for instance in the direction shown by the arrow 57, causing rotation of the twin gears in the direction of arrow 58. This latter rotation is caused by the twin gears travelling around fixed ring gear 39, the cage 45 thereby rotating on its center—the axis of shaft 14. Since there is a difference in ratio between gears 39 and 43 on the one hand and gears 41 and 44 on the other, the planetary movement of gear 44 induces rotation in ring gear 41. The linear travel of the pitch circle of gear 44 is greater than that of the pitch circle of gear 43. Consequently, the gear 41 cannot remain stationary as is gear 39 but is rotated by gear 44 in the direction of arrow 59—a direction opposite to the rotation of shaft 14.

Since the torque of motor 12 is the same on both the stator and the rotor, but opposite, and the ultimate drive imparted to support 26 and drum 11 is counter-clockwise as seen in Fig. 1, the elements 60 of clutch 15 are arranged to lock the drum to the shaft to prevent backup or backlash of shaft 14.

In the capstan shown, assuming speed of rotation of the shaft at about 2700-2800 R. P. M., the general proportions shown of the gears would result in approximately 10 to 12 R. P. M. of the drum in the reverse direction from that of shaft 14.

The power advantage will be clear from the above, being in the nature of one to more than two hundred. Consequently, a load on the end of a rope having one or more turns around the drum, will be easily but slowly pulled by said drum. The slope of face 30 causes a crowding of the turns or convolutions of the rope and, thereby, creates friction between the rope and drum surface 30 that minimizes slippage.

The modification of Figs. 4 and 5 has its power-advantage gear somewhat differently arranged in that the larger gear 44 of each twin gear is in mesh with the sun gear 42. In this form, the linear travel of the larger planetary gear 44 is also greater than that of the smaller gear 43, as before. Actually, the only difference between the gearing of the modification and that of the earlier form is that the ratio between gears 42 and 44 is greater in the modification than the ratio between gears 42 and 43 in the earlier form. Therefore, the gearing of the modification is the more powerful with a somewhat slower output rotation of the drum.

The modification has the lateral extension 17 on its base instead of the means 16. Said extension is shown with an aperture 61 that may be engaged by a hook or the reeve or the bight of a rope to render the capstan captive as to a tree or stump. Fig. 5 shows how a rope may be trained around drum 11 so that the end 62 may be held or restrained with little force while the drum is turned to pull a load on rope end 63. Reversely, the load may be payed out, as can be understood.

It will be noted that clutch 15 is mounted between drum 11 and the hub 36 in the modification. Since said hub is stationary, the backlash feature described above is effected.

While the foregoing has illustrated and described what are now contemplated to be the best modes of carrying out the invention, the constructions are, of course, subject to modification without departing from the spirit and scope of the invention. It is, therefore, not desired to restrict the invention to the particular forms of construction illustrated and described, but to cover all modifications that may fall within the scope of the appended claims.

Having thus described the invention, what is claimed and desired to be secured by Letters Patent is:

1. A capstan comprising a base, a drum disposed above the base, a shaft disposed on the center of rotation of said drum and extending into the base, an electric motor having a field and an armature, the armature of said electric motor being carried by the shaft and the field of said motor being carried by the drum, a one-way clutch engaged with the drum to hold the latter against rotation in one direction an internal gear affixed to the base on the axis of the shaft, a sun gear on said shaft, a planetary gear intermeshing between said internal gear and said sun gear, a second internal gear carried by the drum above the fixed gear, and a second planetary gear fixed to and on the axis of rotation of the first planetary gear and in mesh with said second internal gear.

15 2. A capstan comprising a base, a drum disposed above the base, a shaft disposed on the center of rotation of said drum and extending into the base an electric motor having a field and an armature, the armature of said electric motor being carried by the shaft and the field of

20 said motor being carried by the drum, a one-way clutch engaged with the drum to hold the latter against rotation in one direction an internal gear affixed to the base on the axis of the shaft, a sun gear on said shaft, a planetary gear intermeshing between said internal gear

25 and said sun gear, a second internal gear carried by the drum above the fixed gear, and a second planetary gear fixed to and on the axis of rotation of the first planetary gear and in mesh with said second internal gear, the first planetary gear being smaller diametrically than the second planetary gear and the first internal gear being larger than the second internal gear in the ratio of size of the planetary gears.

3. A capstan comprising a base, a drum disposed above the base, a shaft disposed on the center of rotation of said drum and extending into the base, an electric motor having a field and an armature, the armature of said electric motor being carried by the shaft and the field of said motor being carried by the drum, a one-way clutch engaged with the drum to hold the latter against rotation

35 in one direction an internal gear affixed to the base on the axis of the shaft, a sun gear on said shaft, a second internal gear carried by the drum above the fixed gear, and twin planetary gears on a common axis of rotation, one of said planetary gears being in mesh with the sun gear and said latter gears being in mesh, one with the fixed internal gear and the other with the gear affixed to the drum.

4. A capstan comprising a base, a drum disposed above the base, a shaft disposed on the center of rotation of said drum and extending into the base, an electric motor having a field and an armature, the armature of said electric motor being carried by the shaft and the field of said motor being carried by the drum, a one-way clutch engaged with the drum to hold the latter against rotation

40 in one direction an internal gear affixed to the base on the axis of the shaft, a sun gear on said shaft, a second internal gear carried by the drum above the fixed gear, and twin planetary gears on a common axis of rotation, one of said planetary gears being in mesh with the sun gear and said latter gears being in mesh, one with the fixed internal gear and the other with the gear affixed to the drum.

5. A capstan comprising a base, a drum disposed above the base, a shaft disposed on the center of rotation of said drum and extending into the base, an electric motor having a field and an armature, the armature of said electric motor being carried by the shaft and the field of said motor being carried by the drum, a one-way clutch engaged with the drum to hold the latter against rotation

55 relative to the shaft in one direction an internal gear affixed to the base on the axis of the shaft, a sun gear on said shaft, a second internal gear carried by the drum above the fixed gear, and twin planetary gears on a common axis of rotation, one of said planetary gears being in mesh with the sun gear and said latter gears being in mesh, one with the fixed internal gear and the other with the gear affixed to the drum.

60 6. A capstan comprising a base, a drum disposed above the base, a shaft disposed on the center of rotation of said drum and extending into the base, an electric motor having a field and an armature, the armature of said electric motor being carried by the shaft and the field of said motor being carried by the drum, a one-way clutch engaged with the drum to hold the latter against rotation

65 relative to the shaft in one direction an internal gear affixed to the base on the axis of the shaft, a sun gear on said shaft, a second internal gear carried by the drum above the fixed gear, and twin planetary gears on a common axis of rotation, one of said planetary gears being in mesh with the sun gear and said latter gears being in mesh, one with the fixed internal gear and the other with the gear affixed to the drum.

7. A capstan comprising a base, a drum disposed above the base, a shaft disposed on the center of rotation of said drum and extending into the base, an electric motor having a field and an armature, the armature of said electric motor being carried by the shaft and the field of said motor being carried by the drum, a one-way clutch engaged with the drum to hold the latter against rotation

75 relative to the shaft in one direction an internal gear affixed to the base on the axis of the shaft, a sun gear on said shaft, a second internal gear carried by the drum

above the fixed gear, and twin planetary gears on a common axis of rotation, one of said planetary gears being in mesh with the sun gear and said latter gears being in mesh, one with the fixed internal gear and the other with the gear affixed to the drum, the planetary gear in mesh with the sun gear being larger diametrically than the other planetary gear, and the internal gears being proportional to the difference in size of the planetary gears.

6. A capstan comprising a base provided with a fixed upwardly directed tubular extension, a drum around said extension and extending thereabove, a fixed portion of said drum being disposed within said tubular extension, anti-friction bearings between said portion of the drum and the tubular extension, a motor-driven shaft extending centrally through said portion of the drum, planetary gearing interconnecting the shaft, drum and base to rotate said drum on said bearings and a one-way clutch engaged with the drum to hold the latter against rotation in one direction.

7. A capstan comprising a base provided with a fixed upwardly directed tubular extension, a drum around said extension and extending thereabove, a fixed portion of said drum being disposed within said tubular extension, anti-friction bearings between said portion of the drum and the tubular extension, a motor-driven shaft extending centrally through said portion of the drum, planetary gearing interconnecting the shaft, drum and base to rotate said drum on said bearings, said base having a hollow boss formed therein, and said gearing being disposed within said boss and below the tubular extension of said base, and a one-way clutch engaged with the drum to hold the latter against rotation relative to the shaft in one direction, said clutch being disposed between said drum and shaft.

8. A capstan comprising a base provided with a fixed upwardly directed tubular extension, a drum around said extension and extending thereabove, a fixed portion of

said drum being disposed within said tubular extension, anti-friction bearings between said portion of the drum and the tubular extension, a motor-driven shaft extending centrally through said portion of the drum, planetary gearing interconnecting the shaft, drum and base to rotate said drum on said bearings, said base having a hollow boss formed therein, and said gearing being disposed within said boss and below the tubular extension of said base, and a one-way clutch engaged with the drum to hold the latter against rotation in one direction, said clutch being disposed between said drum and said base.

9. A capstan according to claim 5 in which the base and the drum include portions that cooperate to define an interior space in which the planetary gears are disposed and in which said gears move around the axis of the shaft, a cage carrying said planetary gears, and anti-friction bearings, above and below said gears, mounting the cage on the shaft.

10. A capstan according to claim 5 in which the base and the drum include portions that cooperate to define an interior space in which the planetary gears are disposed and in which said gears move around the axis of the shaft, a cage carrying said planetary gears, and comprising a cage member on each side of said planetary gears, and an anti-friction bearing mounting each cage member on the shaft above and below the gears.
